UNITED STATES PATENT OFFICE.

JACOB L. STAIR, OF CHICAGO, ILLINOIS.

REFLECTOR.

Application filed December 6, 1923. Serial No. 679,017.

My present invention relates to reflectors and has for its principal object the provision of an integral reflector that is so shaped that it will produce a shaft or beam of parallel light rays that may be directed upon an object to be illuminated, and at the same time will throw a general or scattered flood of light that will illuminate the objects or fittings adjacent to the first-mentioned object.

10 The reflector is especially designed for use in the illumination of show windows in the fronts of stores and like places where a general illumination of the window, the floor and background thereof is desired, as well as to concentrate a strong beam of light upon some certain article of wearing apparel or figure or other article of merchandise. This article is usually so placed that it receives the spot beam directly upon it, while the

15 surrounding portions of the window display will be illuminated to a less extent. Such illumination is extremely attractive for the reason that the illuminated object stands out boldly and strongly against the background and the surrounding objects, and thus the attention of observers will be especially directed to the particular object or article sought to be displayed.

Another object of my invention is to provide a reflector that is so shaped that the tip of the lamp or bulb is so positioned therein that the reflector, with the socket and fitting, or bracket, may be laid face down upon a table or other support and the lamp, which is usually of fragile glass, will not be endangered by striking against the support or table. In other words, the tip of the lamp or bulb is back of the plane of the outer edge or rim of the reflector and is protected thereby. It is a further object of my invention to provide a reflector that will have the light bulb or lamp so positioned therein that the light rays emanating therefrom will be shielded from the eyes of persons who may be observing the same from one side, so that the glare from the lamp will not "blind" or dazzle the observer. It is also an object of my present invention to provide a reflector with means that will break up the light rays that are directed outside of the center spot-beam so as to prevent the occurrence of a bright ring or halo surrounding the spot beam. Other objects will be apparent to persons skilled in this art, and I

prefer to carry out my invention and accomplish the aforesaid objects in substantially the manner hereinafter described.

Reference will now be made to the accompanying drawings that form a part of this specification, in which:

Figure 1 is a side elevation of a reflector made in accordance with my invention.

Fig. 2 is an axial vertical section of a portion of the reflector.

Fig. 3 is an enlarged detail showing the manner of corrugating or rippling the skirt of the reflector.

Referring to the drawings, I have employed similar reference characters to designate like parts wherever they occur throughout the several views, and by referring to the drawings it will be seen the reflector is preferably of concavo-convex shape and has a dome-shaped portion A that is of parabolic curvature so that it will reflect parallel light rays therefrom when the lighting unit or lamp is positioned at substantially the axis of the parabola. The upper portion of this dome A is provided with a central opening to accommodate the lamp or bulb, and the reflector surrounding this opening is provided with an upwardly tapering neck portion B, the upper edge thereof being flared outwardly to provide a rim C with which the holder or clamping unit co-operates to support the reflector in position. This tapered neck is of such dimensions that the bulb may be readily accommodated and provides a space between the bulb and the reflector for the circulation of air therebetween. The interior of the reflector so far described is smooth and is preferably silvered to assist in reflecting all of the light rays reaching the surface thereof from the lamp or bulb.

Extending parallel to the axis of the reflector and continuing concentric thereto from the lower edge of the dome portion A, is a skirt or extension D of cylindrical section. The outer edge of this skirt flares outwardly as seen to provide a suitable rim E to which colored light screens may be secured whenever a shaded or colored illumination is desired. The skirt portion D just described is provided with oblique corrugations F that are formed on a compound curve as delineated in detail in Figure 3, and this skirt is also waved slightly as at

G, the waves or undulations being disposed transversely of the skirt and extending longitudinally of the axis of the cylinder formed by said skirt. These corrugations and undulations cross each other and tend to break up the light rays so as to thereby prevent the rays emanating from the skirt from forming a bright ring or halo of light around the area illuminated by the beam. In other words, the light rays reflected from the skirt are scattered and broken up to such an extent that an even tone of light is projected therefrom. It is obvious that other means of breaking up the light may be used upon the skirt, but I prefer, in carrying out my invention, to employ the method herein shown and described, and I therefore desire it understood that such other methods are fully contemplated as coming within the scope of my appended claims.

What I claim is:

1. A reflector comprising a parabolic reflecting element, and a cylindrical reflecting element extending from the outer edge thereof concentric with the axis of the body, the reflecting surface of said cylindrical element being provided with longitudinal

waves and parallel corrugations oblique thereto.

2. A reflector comprising a hollow body 30 the central inner reflecting surface of which is formed to direct light therefrom in parallel rays, the edge portion of said body formed with a skirt of true cylindrical shape 35 having its reflecting surface provided with longitudinal and transverse striations whereby to minutely break up and diffuse the light rays around the parallel rays.

3. A reflector comprising a concave reflecting element, and a concentric cylindrical 40 skirt extending from the outer edge thereof, said concave element provided with a smooth reflecting surface and said skirt formed with waves extending longitudinally and corrugations extending obliquely thereto, whereby said concave element will project direct light rays to form a zone of 45 bright illumination and said skirt will project a halo of diffused illumination outside of said bright zone.

Signed at Chicago, county of Cook and State of Illinois, this 21st day of November, 1923.

JACOB L. STAIR.
